Primary Examiner — Cynthia R Underwood

(72) Inventor: **Shunchao Tang**, Shenzhen (CN)

(57) **CLAIM**

(73) Assignee: **SHENZHEN TANGNISEN TECHNOLOGY CO., LTD.**, Shenzhen (CN)

The ornamental design for a protective cover for electronic equipment, as shown and described.

(**) Term: **15 Years**

DESCRIPTION

(21) Appl. No.: **29/701,028**

(22) Filed: **Aug. 7, 2019**

(51) LOC (12) Cl. **14-02**

FIG. 1 is a perspective view of a protective cover for electronic equipment showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof.

FIG. 9 is a perspective view of the protective cover for electronic equipment shown in a first configuration of use;

FIG. 10 is a perspective view of the protective cover for electronic equipment shown in a second configuration of use;

FIG. 11 is a perspective view of the protective cover for electronic equipment shown in a third configuration of use;

FIG. 12 is a perspective view of the protective cover for electronic equipment shown in a fourth configuration of use;

and,

FIG. 13 is an enlarged partial view of portion 13 of FIG. 1. The broken lines in FIGS. 1 and 13 depict the area from which the FIG. 13 enlargement was taken and form no part of the claim. The broken lines depicting a tablet form no part of the claim. The thicker broken lines are stitching and are part of the claim.
